US0D1032709S

(12) **United States Design Patent** (10) Patent No.: **US D1,032,709 S**
(45) Date of Patent: ** Jun. 25, 2024

(54) **EYEWEAR FRAME**

(71) Applicant: **PAIR EYEWEAR, INC.**, New York, NY (US)

(72) Inventors: **Nathan Kondamuri**, Brooklyn, NY (US); **Sophia Edelstein**, Brooklyn, NY (US)

(73) Assignee: **PAIR EYEWEAR, INC.**, New York, NY (US)

(**) Term: **15 Years**

(21) Appl. No.: **29/877,594**

(22) Filed: **Jun. 8, 2023**

(51) LOC (14) Cl. **16-06**

(52) U.S. Cl.

USPC **D16/328**

(58) **Field of Classification Search**

USPC D16/300, 306, 312, 313, 321, 326, 327, D16/328, 329; D11/201; D29/102, 104, D29/105, 107, 108, 109, 110; D24/110.1, D24/110.2, 110.3

CPC G02C 1/00; G02C 7/02

(57) **CLAIM**

The ornamental design for an eyewear frame, as shown and described.

DESCRIPTION

FIG. 1 is a front perspective view of an eyewear frame.

FIG. 2 is a rear perspective view of the eyewear frame.

FIG. 3 is a front view of the eyewear frame.

FIG. 4 is a rear view of the eyewear frame.

FIG. 5 is a left side view of the eyewear frame.

FIG. 6 is a right-side view of the eyewear frame.

FIG. 7 is a top view of the eyewear frame; and,

FIG. 8 is a bottom view of the eyewear frame.

The broken lines in the drawings are shown to depict portions of the eyewear frame that form no part of the claimed design.

1 Claim, 6 Drawing Sheets
